UNITED STATES PATENT OFFICE.

PAUL PIGNOT, OF YONKERS, NEW YORK, ASSIGNOR TO ALEXANDER SMITH & SONS CARPET COMPANY, OF SAME PLACE.

DESIGN FOR A CARPET.

SPECIFICATION forming part of Design No. 13,989, dated June 19, 1883.

Application filed May 4, 1883. Term of patent 3½ years.

To all whom it may concern:

Be it known that I, PAUL PIGNOT, of Yonkers, Westchester county, New York, have invented a new and original Design for Carpets, 5 of which the following is a specification.

The accompanying photograph illustrates my new design for carpets.

This invention relates to a new design for carpets, oil-cloths, and analogous fabrics; and 10 it consists of the new ornamentation of parts, hereinafter more fully pointed out.

In the center of the carpet is a frame containing a picture representing a landscape, A. Above this frame is a cluster of roses, B, with

appropriate leaves. Below it is a cluster, C, 15 of flowers, and below this, again, a spray, D, of flowers. The spaces between these floral ornaments B C D are irregular fields of varying tints or shades, which affect the character of the entire design.

I claim—

The design for carpets, consisting of the frame A and floral ornaments B C D, substantially as shown:
